UNITED STATES PATENT OFFICE

2,544,332

VIBRATOR INTERRUPTER SYSTEM

Robert H. Lee, Indianapolis, Ind., assignor, by
mesne assignments, to Cornell-Dubilier Elec-
tric Corporation, South Plainfield, N. J., a cor-
poration of Delaware

Application August 16, 1946, Serial No. 690,993

3 Claims. (Cl. 318—37)

1

The present invention relates to vibrating in-
terrupter systems, and more particularly to vi-
brating interrupter systems having a plurality
of interrupters, which it is desired to operate at
synchronous frequency in phase.

It is one of the objects of the invention to pro-
vide a system for the operation of at least two
vibratory interrupters at synchronous frequency.

Another object of the invention is the provi-
sion of means for maintaining the operation of
at least two vibratory interrupters at the same
frequency, by decreasing the frequency of that
vibrator interrupter which has a tendency to
vibrate at a higher frequency.

Another object of the invention is the pro-
vision of means for automatically lowering the
frequency of that vibratory interrupter, which
has a tendency to vibrate at a higher frequency.

It is one of the objects of the invention to pro-
vide means for maintaining more than two vi-
bratory interrupters at the same frequency.

It is a still further object of my invention to
provide a means by which a plurality of vibrating
interrupters may be maintained substantially in
phase during their operation.

For the purpose of describing the invention, I
have illustrated certain embodiments thereof in
the accompanying drawings, in which:

Fig. 1 is a diagrammatic view of a circuit ar-
rangement of a system embodying my invention;

Fig. 2 is a diagrammatic view of a circuit ar-
rangement showing a modification of my inven-
tion;

Fig. 3 is a diagrammatic view of a circuit ar-
rangement embodying a further modification of
my invention;

Fig. 4 is a diagrammatic view of a circuit ar-
rangement for carrying my invention, in connection
with more than two vibrator interrupters;
and

Fig. 5 is a side elevation of a vibrator inter-
rupter of a type to be used in connection with
my invention.

Referring to the vibrator interrupter illustrated
in Fig. 5, the vibrator interrupter comprises a
suitable frame comprising a pair of side mem-
bers 1 connected at one end by a substantially
U-shaped crosspiece 2, the two side legs of which
are secured to the side pieces 1 by screws or bolts.
A driving magnet comprising a coil 3 surround-
ing a pole 4 is secured to the crosspiece 2 by a
screw entering the top of the pole 4.

A vibrator reed 5 having an armature 5' carries
contacts 6 and 7 and operates between a pair
of side arms carrying contacts 10 and 11. The

reed 5 also carries a resilient arm 12 carrying
the contact 13 adapted for cooperation with a
contact 14 mounted on one of the side members
1. The reed 5 and its associated contact arms
8 and 9 are clamped between the side arms 1 in
a suitable stack 15 provided with the necessary
insulating spacers for insulating the arms 8 and
9 from one another, the center reed and the
frame. For the purpose of convenience, the con-
tacts 6, 7 and 10 and 11 may be referred to as
the power contacts and the contacts 13 and 14
as the driver contacts.

In the operation of such a structure, the driver
contacts 13 and 14 are normally closed and the
armature 5' is off center with the respective face
of the pole 4 in such a manner that when the
magnet is energized, the armature will be at-
tracted and swing by the exerted magnetic force.
Therefore, upon the closing of the circuit through
the magnet 3 which will set up a vibration in
the reed 5, the reed will be moved in a direction
to open one pair of power contacts and close the
other pair and also open the driver contacts.
With the opening of the driver contacts, the reed
will swing in the opposite direction opening the
initially closed power contacts and closing the
opposite power contacts. However, due to the
mounting of the contacts and arrangement of
the parts, the power contacts will open prior
to the opening of the driver contacts. The break
in the driving coil circuit through the driving
contacts is so timed that the driving magnet is
completely deenergized by the time the armature
passes the center of the magnetic force of the
magnet, so that there will be no residual mag-
netism in the pole to affect the amplitude of
the reed, as it continues its oscillation in the
direction initiated by the magnet. If the ener-
gization of the driving magnet is continued after
the armature has passed the center of the mag-
netic force of the pole, it would tend to exert
a pull on the reed against its continued move-
ment, thereby having a damping effect on the
reed, decreasing its amplitude.

There are in the commercial art types of vi-
brator interrupters which can be so adjusted
that the damping of the vibratory reed thereof
will result in the lowering of the frequency of the
reed, and in this present system, I take advantage
of this characteristic to provide automatic means
for controlling the damping of the reed and there-
by controlling the frequency of the reed.

This damping feature of the vibrator is taken
advantage of by me, and in my system I provide
means for locking a plurality of vibrator inter-

rupters in phase and maintaining a synchronous frequency of the vibrating reeds of the different vibrator interrupters. To this end, by the provision of my invention, as illustrated in Figs. 1 to 4, I am enabled to prolong the energization of the magnet of that vibrator interrupter which tends to lead the other vibrators in phase relationship and thereby damp that vibrating reed sufficiently to bring it back to a substantially in phase relationship with the other reed.

Referring to Fig. 1 of the drawing, I provide a pair of vibrator interrupters 17 and 18, the vibrator interrupter 17 having a vibrating reed 19 and the vibrator interrupter 18 having a vibrating reed 20. The reed 19 vibrates between a pair of side contacts 21 and 22 respectively connected to the outer terminals of a primary winding 23 of a transformer, which transformer is provided with a secondary winding 24. The center tap of the winding 23 is connected to one side 25 of a source of power, which may be a battery or any other direct current source. The reed 19 is connected to the opposite side 26 of the source of power. The driving coil 27 of the reed 19 has one terminal connected to the side 25 of the source of power, the opposite terminal being connected to a driver contact 28 normally in contact with a contact on the reed 19.

The power contacts 29 and 30, of the vibrating interrupter 20, are respectively connected to the opposite terminals of a primary winding 31 of the transformer, the center tap of this winding being connected to one side 25 of the source of power. The reed 20, like the reed 19 is connected to the side 26 of the source of power. The driving coil 32 of the reed 20 has one terminal connected to one side 25 of the source of power and the opposite terminal is connected to a driver contact 33 normally in engagement with a contact on the reed 20. Across the terminals of the driving coils 27 and 32, connected to contacts 28 and 33, is connected a condenser 35' having in series therewith a resistance 36'.

In operation, as the vibrating reeds 19 and 20 vibrate respectively between the power contacts 21 and 22 and 29 and 30, the circuit will be closed in one direction through the corresponding halves of the primary windings 23 and 31 and then in the opposite direction through the other halves of the windings, thereby developing an alternating current voltage in the secondary 24 of the transformer.

In commercial practice, where a plurality of vibrators are used for controlling a given circuit, the vibrating reeds will tend to operate at different frequencies. It is mechanically almost impossible to construct two vibrating interrupters so that they will vibrate at exactly the same frequency. Under such circumstances, referring to the system illustrated, the vibrating reeds 19 and 20 would tend to operate at different frequencies.

The condenser 35', however, provides means for damping that vibrator which tends to vibrate at the higher frequency. Furthermore, the means used forces that vibrator which would tend to vibrate at the higher frequency to stay in very close phase relationship to the naturally slower vibrator. It will be assumed, for the purpose of illustration, that reed 19 leads reed 20 by a small phase angle. It is further assumed that the two vibrators are approaching that position at which the driver contacts 28 and 33, are about to separate from contact with vibrating reeds 19 and 20. Since the reed 19 is leading

the reed 20, the driver contact 28 will leave contact with the reed 19 before the driver contact 33 leaves contact with the reed 20. The condenser 35' has been shorted out previous to the instant that either driver contact loses contact with either center reed and it therefore has no charge at the instant driver contact 28 loses contact with reed 19. I have thus defined the conditions of the driver portion of the circuit at the instant of time at which action tending to synchronize the vibratory reeds starts.

It must be pointed out that the position of the driver contact in a vibrator is set in such a way that the maximum of drive is transmitted from the coil to the vibrating reed. If current is not interrupted at the instant the driver contact of the vibrator leaves the vibrating center reed, then the center reed will be damped. It must further be pointed out that the driving coil 20 of the vibrator is a reactor. Therefore, once current has been set up in the driver coil, the magnetic field in that coil tends to maintain that current at its existing value. With these fundamental concepts in mind, it is now possible to understand the action of the illustration as detailed below.

Assume now, that because reed 19 is leading reed 20, driver contact 28 has left the center reed 19, whereas driver contact 33 is still in contact with the reed 20. The condenser 35' provides an alternate path of current for coil 27. Coil 27 at the instant the circuit has broken at contact 28 has reached its peak value of current flow. The magnetic field maintains this current flow and the current passes through condenser 35' to driver contact 33 and through to center reed 20. Since any current flow through coil 27 maintains its magnetic pull, and since magnetic pull, after driver contact 28 leaves center reed 19, tends to damp center reed 19, the center reed 19 is slowed down. The amount of current flow through condenser 35' can be controlled by the value of the condenser. This is true because as condenser 35' becomes charged due to the current flow from coil 27, it sets up a voltage in opposition to the direction of current flow. Thus, we have a control on the amount of damping action caused by said current flow through coil 27. The value of this condenser is chosen so that the damping action on the faster vibrating reed 19 will just bring it back into phase with vibrating reed 20. This value is not at all critical, since the effective action takes place only during a very small portion of the complete cycle of the vibrating center reeds. The important feature is that it be large enough to permit a sufficient current flow during the effective portion of the cycle in which the damping takes place, and yet not so large that current flow is maintained through a major portion of the cycle. At a time after driver contact 28 loses contact with reed 19, driver contact 33 loses contact with reed 20. This immediately suspends current flow in both coil 27 and coil 32. Thus, the lagging reed 20 gets its full drive from coil 32, whereas reed 19 got full power from coil 27 and then received a damping action from coil 27.

After both reeds 19 and 20 have left driver contacts 33 and 28, and have swung to their maximum position away from the driver contacts, a further important action takes place in the circuit. Namely, the condenser 35' discharges to return to its original condition of zero charge. The action takes place as follows. During the time when driver contact 28 was out of contact

with reed 19 and driver contact 33 was in contact with reed 20, a voltage "E" was built up across condenser 35 due to the charge flowing into it from coil 21. After both reeds have left their respective driver contacts and are traveling toward their zenith, the condenser 35 discharges through coils 32 and 21. The current flow through coil 32 is in the same direction as it was during contact of driver contact 33 with reed 20. The current flow through coil 21 is in a direction opposite to that which it was during contact of driver contact 28 with reed 19. This discharge takes place after reeds 19 and 20 are so far out of range of the magnetic fields in the coils that the effect thereof is negligible, and therefore the current flow due to the discharge of condenser 34 has no effect upon the action of the reeds.

Throughout the balance of the cycle the vibrators act as they normally do, that is, they get normal driving power up to the point where the damping action on the leading vibrator again takes place. In this way, the two vibrators are held not only at the same frequency, but also substantially in the same phase. The result of the synchronizing action is that the power points 29 and 21 get their power simultaneously, and the power is broken simultaneously. On the other half cycle power points 22 and 30 receive power simultaneously, and the power is interrupted simultaneously.

In the system illustrated in Fig. 3, I have shown a modification of my invention wherein instead of the control being effected through the driving contacts, I have provided for the control being effected through the power contacts. In the arrangement illustrated in Fig. 3, the driving coil 27 has connected across one terminal thereof and the power contact 29 of the vibratory member 18, a condenser 35 having arranged in series therewith a protective resistance 36. The driving coil 32 has connected across one terminal thereof and the contact 22 of the vibratory interrupter 17, a condenser 37 having a protective resistance 38 in series therewith. With the reeds 19 and 20 respectively engaging contacts 28 and 33, condenser 35 will be charged from the battery through reed 19, contact 28 and condenser 35, the top half of the primary winding 31 to battery. Condenser 37 will be charged from reed 20, contact 33 and condenser 37, the top half of primary winding 31 back to the opposite side of the battery. Assuming that vibratory reed 20 is the leading contact, the break at contact 30 and engagement of contact 29 will be somewhat ahead of the break with the contact 21 and the engagement of the contact 21 with the result that condenser 35 will discharge through the driver contact 28 and the driver contact 29 with the result that there will be little or no effect on the winding 27 of the lagging reed 19. At the same time after reed 20 leaves contact 33, condenser 37 will discharge through the coil 32, through the battery and back to the opposite side of the line. This results in a surge of current through the coil 32 which in turn results in a damping action on the reed 20 thus bringing it into phase with the reed 19. On the reverse half of the cycle, a similar action takes place. However, the surge of current through the coil of the leading vibrator comes at such a time as to damp that reed. Whereas, the surge of current through the coil of the lagging vibrator arrives at such a time as to aid that reed.

In the arrangement illustrated in Fig. 2, I have provided a system whereby I take advantage of

the combined effects of the arrangements illustrated in Figs. 1 and 2. In this system, a condenser 39 and protective resistance 38' are connected across the driving contacts 28 and 33. A condenser 40 having a protective resistance 41 in the circuit thereof, is connected across a terminal of the driving coil 27 of the vibratory interrupter 17 and the power contact 30 of the vibratory interrupter 18. A similar condenser 42 having a protective resistance 43 in the circuit thereof is connected across the power contact 21 of the vibratory interrupter 17 and a terminal of the driving coil 32 of the vibratory interrupter 18. By this arrangement, I am enabled to get a much closer regulation of the two vibratory reeds 17 and 18, than I am with either of the arrangements illustrated in Figs. 1 and 3. In some respects, the condenser 39 provides a bypass for the condensers 40 and 42. In each instance, however, with respect to the arrangements illustrated in Figs. 1, 2 and 3, there is a damping action on the leading vibratory reed, which action tends to reduce the amplitude of the reed and thus reduce the frequency of the reed until the frequency of the reed which will normally lead will be in synchronism with the frequency of the reed which would normally lag and the reed will be maintained in phase.

In the arrangement illustrated in Fig. 4, I have shown a modification wherein more than two, in the arrangement shown three, vibratory interrupters are maintained in synchronism and in phase lock. In the arrangement illustrated in Fig. 4, three vibratory interrupters 44, 45 and 46 are provided for controlling the primary windings 47, 48 and 49 of the transformer having a secondary winding 50. The vibratory interrupter 44 is provided with a center reed 51 operating between power contacts 52 and 53, and being driven by a driving coil 54 having one terminal connected with a driver contact 55 and its opposite terminal connected to one side 56 of a direct current source of supply.

The vibratory interrupter 45 is provided with a center reed 57 operating between the power contacts 58 and 59 and having a driving coil 60 controlled by the driver contact 51.

The vibratory interrupter 46 is provided with a center reed 62 operating between the power contacts 63 and 64 and driven by a driving coil 65 having one terminal connected to a driver contact 66. Each of the reeds 51, 57 and 62 is connected to the opposite side 67 of the source of direct current supply. Each of the windings 47, 48 and 49 is provided with a center tap connected to the lead 56 of the supply circuit. Each of the coils 54, 60 and 65 has one terminal connected to the supply line 56, so that in operation, the reeds 51, 57 and 62 will be driven by their respective driving coils.

Substantially the same arrangement for maintaining the vibrator reeds in synchronism is used in the arrangement shown in Fig. 4, as is shown in Fig. 2. A condenser 83 with a protective resistance 84 in series therewith is connected between the terminals of the driving coils 54 and 60 and across the contacts 55 and 61. A second condenser 67 with a protective resistance 68 is connected between the terminals of the driving coils 60 and 65 and across the contacts 61 and 66 and a third condenser 69 in series with a protective resistance 70 is connected between terminals of the driving coils 65 and 54 and across the contacts 55 and 66. In operative effect, the condensers 83, 67 and 69 act in substantially the

same manner as the condenser 39 in the arrangement illustrated in Fig. 2. For instance, if the reeds 51 and 62 tend to lead the reed 57, then a damping current would be maintained through the condensers 83 and 67 through contact 61. If, however, the reed 62 happens to be the lagging reed, then the damping current for the driving coils 60 and 54 would be through the condensers 67 and 69 and the contact 66. It is, therefore, apparent from the arrangement, that I have provided a damping current surge for the driving coil, of whichever reed or reeds happen to lead the reed having the greatest tendency to lag through a condenser or condensers to the driver contact of the reed which tends to lag.

Supplementing the above action or cooperating with the respective condensers 83, 67 and 69, I provide a series of condensers operating in substantially the same manner as is disclosed in Fig. 2. To this end, one terminal of the coil 54 is connected through a condenser 79 and resistance 80 with the contact 58 and likewise through the condenser 77 and resistance 78 with the contact 63. One terminal of the coil 60 is connected through a condenser 81 and the resistance 82 to contact 52 and also through the condenser 75 and resistance 76 with contact 63. Likewise, one terminal of the coil 65 is connected through the condenser 73 and resistance 74, with the contact 52 and through the condenser 71 and resistance 72 with the contact 58. Accordingly, with the arrangement I have provided condensers corresponding to condensers 40 and 42 of Fig. 2 and their respective resistances for cooperating with whichever of the plurality of vibrator reeds happens to tend to lead.

I claim as my invention:

1. In combination with at least a first vibrating interrupter and a second vibrating interrupter, said first and second vibrating interrupters each including contact means, a vibrating contact member cooperating therewith and a driving magnet having a coil intermittently energized from a direct current source through the vibrating contact member, said vibrating contact members being mechanically independent, of means for operating the vibrating contact members of said first and second vibrating interrupters at substantially the same frequency comprising connecting means for connecting a terminal of the driving magnet of the first vibrating interrupter with a contact cooperating with the vibrating contact member of said second vibrating interrupter and a terminal of the driving magnet of said second vibrating interrupter with a contact cooperating with the vibrating contact member of said first vibrating interrupter, said connecting means including a condenser.

2. A system for converting current from a direct current source into alternating current, said system having at least a first vibrating interrupter circuit and a second vibrating interrupter circuit, said first and second vibrating inter-

rupter circuits, each including contact means including a vibrating contact member and a driving magnet having a coil intermittently energized from a direct current source through the vibrating contact member said vibrating contact members being mechanically independent, and means for operating the vibrating contact members of the first and second vibrating interrupters at substantially the same frequency, which comprises

5 connecting means connecting the coil of the driving magnet of the first vibrating contact member in circuit relation with a condenser and a contact cooperating with the vibrating contact member of the second vibrating interrupter and a second connection means connecting the coil of the driving magnet of the second vibrating contact member in circuit relation with a condenser and a contact cooperating with the vibrating contact member of the first

20 interrupter.

3. A system for converting current from a direct current source into alternating current, said system including at least a first vibrating interrupter circuit and a second vibrating interrupter

25 circuit, said first and second vibrating interrupter circuit, each including a driving magnet having a coil, a vibrating contact member, a driving contact cooperating with said vibrating contact member for intermittently energizing the driving

30 magnet coil from the direct current source and a power contact, the improvement for operating the vibrating contact members of the first and second vibrating interrupter circuits at substantially the same frequency, which comprises

35 connecting means for connecting the coil of the driving magnet of the first vibrating contact member in circuit relation with the driving contact of the second vibrating interrupter circuit and the driving magnet coil of the second vibrating contact

40 member with the driving contact of the vibrating interrupter of the first vibrating interrupter circuit, said circuit connections including a condenser, means for connecting the driving coil of the vibrating contact member of the first circuit

45 with a power contact of the vibrating interrupter of the second circuit, said means including a condenser, and means for connecting the driving coil of the second vibrating contact member with a power contact of the first vibrating circuit inter-

50 rupter, said means including a condenser.
